Des. 154,065

COMBINATION FISHING ROD AND WALKING CANE

Filed June 5, 1947

UNITED STATES PATENT OFFICE

154,065

DESIGN FOR A COMBINATION FISHING ROD
AND WALKING CANEHarvey M. Phillips and Harry H. Boucher,
Dallas, Tex.

Application June 5, 1947, Serial No. 139,458

Term of patent 14 years

(Cl. D31—4)

To all whom it may concern:

Be it known that we, Harvey M. Phillips and Harry H. Boucher, both citizens of the United States, and both residing at Dallas, in the county of Dallas, and State of Texas, have invented a new, original, and ornamental Design for Combination Fishing Rod and Walking Cane, of which the following is a specification, reference being had to the accompanying drawing, forming part thereof.

Figure 1 is an elevation of a combination fishing rod and walking cane showing our new design, and illustrating the tubular rod case connected with the rod handle.

Figure 2 is an elevation showing the handle illustrated in Figure 1 with the rod case removed, and showing the assembled rod joints attached to said handle, and

Figure 3 is an enlarged elevation of the lower end of Figure 2.

The tubular housing illustrated in Figure 1 is not shown in Figures 2 and 3.

We claim:

The ornamental design for a combination fishing rod and walking cane, substantially as shown and described.

HARVEY M. PHILLIPS.
HARRY H. BOUCHER.
